UNITED STATES PATENT OFFICE

141,046

DESIGN FOR A FIGURINE OR SIMILAR ARTICLE

Frances Keeney, Kansas City, Kans., assignor to Hall Brothers, Incorporated, Kansas City, Mo., a corporation of Missouri

Application August 14, 1944, Serial No. 114,881

Term of patent 14 years

(Cl. D29—24)

To all whom it may concern:

Be it known that I, Frances Keeney, a citizen of the United States, residing at Kansas City, in the county of Wyandotte and State of Kansas, have invented a new, original, and ornamental Design for a Figurine or Similar Article, of which the following is the specification, reference being had to the accompanying drawing, forming part thereof.

Fig. 1 is a perspective view of the front of a figurine or similar article showing my new design.

Fig. 2 is a rear perspective view thereof.

I claim:

The ornamental design for a figurine or similar article, as shown.

FRANCES KEENEY.
